UNITED STATES PATENT OFFICE.

JOSEPH F. LAMB, OF NEW BRITAIN, CONNECTICUT, ASSIGNOR TO LANDERS, FRARY & CLARK, OF NEW BRITAIN, CONNECTICUT, A CORPORATION OF CONNECTICUT.

PROTECTIVE DEVICE FOR ELECTRICALLY-HEATED UTENSILS.

1,060,266.

Specification of Letters Patent.

Patented Apr. 29, 1913.

Application filed December 13, 1912. Serial No. 736,526.

To all whom it may concern:

Be it known that I, JOSEPH F. LAMB, a citizen of the United States, and a resident of New Britain, in the county of Hartford and State of Connecticut, have invented certain new and useful Improvements in Protective Devices for Electrically-Heated Utensils, of which the following is a specification.

10 The object of the invention is to provide means for automatically breaking the circuit of an electrical heater at a predetermined temperature, which is a little lower than a temperature which would destroy or injure 15 the heater or the utensil, thus acting as a guard to protect the device in case it is inadvertently left with the current on when it is empty.

20 In the drawings which illustrate an embodiment of the invention Figure 1 is a side elevation partly in section, Fig. 2 is the bottom view of the heater.

25 In the drawings *a* denotes a receptacle, *b* its base, and *c* the complete heater; *d* and *e* represent the circuit wires, the wire *e* being broken and connected with the terminals 1, 10, which, as seen, are spaced apart. These terminals may be conveniently mounted on a part of the heater and insulated therefrom, and, as shown, they project through insulating sleeves 2, 12, into a tubular hub 13, which is threaded to receive a tubular bushing 14, provided with an insulating lining 15 which supports a tube of lead or 30 other suitable metal, which contacts with the spaced terminals 1, 10 and provides an electrical connection between them. If the utensil is empty and the current left on, the heat will soon rise to a point where the lead sleeve will be melted and the circuit between the terminals 1, 10, broken. As the lead melts it will run out through the tubular bushing and so keep the seat in the insulating lining free and clear. In order to 35 reestablish the circuit connections it is only necessary to remove the bushing 14, remove what is left of the lead connector and insert another one, replacing the bushing in position in the hub to connect up the two terminals.

40 Having now described one embodiment of the invention I desire it to be understood that it is my intention to cover any alterations or modifications which may come within the scope of the appended claims.

I claim as my invention:

1. The combination with an electrical heater, a pair of spaced terminals connected into the circuit of said heater, and a holder, of a connector having a relatively low fusing point, formed separately from but clamped between said terminals and holder. 60

2. The combination with an electrical heater having a normally broken circuit of a connector made of material fusible at a 65 relatively low temperature, and a holder formed at least in part of insulating material, engaging said connector to hold it in contact with the adjacent ends of the broken circuit. 70

3. The combination with an electrical heater and a pair of spaced terminals connected into the circuit of said heater, of a tubular hub within which the ends of said terminals project, a bushing threaded into 75 the end of said hub, an insulating lining in said bushing, and a connector of metal fusible at a relatively low temperature separated from but supported by said insulating lining in contact with said terminals. 80

4. The combination with an electrical heater and a pair of spaced terminals connected into the circuit of said heater, of a tubular hub within which the ends of said terminals project, a tubular bushing threaded into the end of said hub, an insulating lining in said bushing, and a tubular connector of metal fusible at a relatively low temperature supported by said insulating lining in contact with said terminals. 85

5. The combination with an electrical heater and a pair of spaced terminals connected into the circuit of said heater, of a tubular hub within which the ends of said terminals project, a tubular bushing threaded into the end of said hub, an insulating lining located within the bushing and having an inwardly inclined seat, and a tubular connector of metal fusible at a relatively 95 low temperature supported on the seat in 100 the insulating lining and held in contact with the terminals.

6. The combination with an electrical heater and a pair of spaced terminals connected into the circuit of said heater, of a tubular hub depending from the underside 105 of the heater and having aligned apertures through which said terminals project, insulating linings in the apertures, a connector made of metal having a relatively low fus- 110

2

ing point located within said hub in contact with said terminals, a holder for said connector, means for supporting said holder in position, and insulation interposed between the connector and the hub.

7. The combination with an electrical heater and a pair of spaced terminals connected into the circuit of said heater, of a holder recessed in one end, a connector lo-

cated in the recess in said holder, insulating material interposed between the holder and connector, and means for supporting said holder to position and maintain said connector in contact with said terminals. ¹⁰
